UNITED STATES PATENT OFFICE.

OSCAR L. SCALBOM, OF GLENVIEW, ILLINOIS.

CUTTER DEVICE.

1,248,554.

Specification of Letters Patent.

Patented Dec. 4, 1917.

Application filed December 17, 1909. Serial No. 533,663.

To all whom it may concern:

Be it known that I, OSCAR L. SCALBOM, a citizen of the United States, and a resident of Glenview, in the county of Cook and State of Illinois, have invented certain new and useful Improvements in Cutter Devices, of which the following is a specification.

My present invention relates to cutter devices generally and contemplates more especially the provision of a conveniently operable portable device for pointing, and re-pointing, the bamboo "reproducer needles" used in connection with sound reproducing machines, and for cutting fibrous and other hard resistant materials having a tendency to splinter or fray at the edges when submitted to ordinary cutting operations.

The principal objects of my invention are the provision of a simple device of the character described which may be produced at a sufficiently low cost to permit the users of phonographs and other consumers of such "reproducer needles" to resharpen the needles and thereby multiply many times the present life of such needles instead of having to discard them and renew the stock at some little expense and inconvenience.

Further objects of my invention are the provision of a cutter characterized as above indicated, by the use of which such reproducer needles may be provided with fine, sharp and clean points; the provision of means whereby the cutter members may be forced into close contact with each other; the provision of compensating means whereby a moving cutter may be held in intimate contact with the stationary cutter, or vice versa, as the device tends to wear in service; the provision of means whereby a minimum amount of material is removed from the needle at the time the cutting operation is effected; the provision of means whereby after the completion of the cutting operation, the device is restored to operative position, and generally to produce a device of the character referred to which will be simple and inexpensive in manufacture, efficient and accurate in operation, and unlikely to get out of order, and one in which the wearing parts may be readily and inexpensively replaced when necessary, together with such other objects as will hereinafter appear.

Heretofore, the operation of pointing and

repointing fiber reproducer needles has been carried out effectively only by the means of power operated machines of relatively large cost and considerable weight, which are not ordinarily available to the users of phonographs employing fiber needles, and owing to the necessity of insuring the closest possible contact at all times between the cutter devices in order that the needles may be sharply and cleanly pointed, such power operated machines have embodied therein certain more or less complex and hence undesirable features of construction, rendering the machines less efficient. To overcome these objections, as well as to accomplish the objects above stated and gain certain further advantages, I have provided a construction, one exemplification of which is illustrated in the accompanying drawings, wherein—

Figure 1 is an elevational view, partly in section of one side of a device embodying my invention in preferred form;

Fig. 2 is an elevational view regarding the left hand end of the device of Fig. 1; and

Fig. 3 is a sectional view taken on the line III—III of Fig. 1, looking in the direction indicated by the arrow;

Fig. 4 is a view illustrative of a reproducer needle pointed by the machine of Figs. 1 to 3.

Referring now more particularly to Fig. 1, it will be observed that in carrying out my invention I provide a stationary base 10, preferably of cast metal covered by some soft material, such as felt, as indicated at 11. On the base 10 are a pair of upstanding ears 12 between which the cutter head 13 is pivoted as indicated at 14. At the opposite end of the head I provide a movable cutter 15 bifurcated at its upper end as indicated at 16—16', and engaging such head by means of the pin 17. The base 10 is likewise provided with a pair of upstanding ears 18 to which is pivoted the stationary cutter plate 19 by means of the pins 20.

The cutter plate 19 in turn carries the needle rest 21, secured thereto by a set screw 22, which rest is provided with a guide 23, preferably disposed diagonally thereupon, to the end that the cut given the needle may be at an angle of approximately 40° to the longitudinal axis of the needle. The rest 21, I find in practice, should be set at an angle of about 40° relatively to the horizon-

tal in order to make the point on the needle of the greatest feasible angularity and fineness. To the end that a minimum amount of material may be removed from the needle by the cutting operation I employ as a stop for the needle the spring 24 mounted in the ears 25 formed on the base 10, which as here shown also serves to force the cutter 15 into contact with the cutter plate 19.

10 To insure the closest possible contact between the cutter 15 and the cutter 19, when the head 13 is actuated by being struck at 26, and thereby not only to assure the formation of a clean point on the needle but 15 also that such point may be slightly tapered and of exceeding fineness, I provide a spring 27 inserted under compression in the housing 28 in said head, the free end of said spring exerting a constant pressure on the 20 said cutter 15, holding it in contact with the cutter 19; and further provide a spring 29 inserted under compression in the housing 30 formed in the base 10, the outer end of such spring exerting a constant pressure 25 on the base 31 of the rest 21, mounted upon the cutter 19.

For the purpose of restoring the device to operative position (as observable in Fig. 1) after impact upon the head 13 or other depression of such head, I provide a spring 32 inserted under compression in a housing 33 in the base 12, the free end of such spring bearing against an arm 34 provided on the head 13, by means of which construction 35 the head is maintained in an elevated position with the edge 35 of the cutter 15 a substantial distance above the cutting edge 36 of the cutter plate 19 and above the guide 24.

As will be obvious upon an inspection of 40 the drawing, the cutter 15 is restrained in its movement to the left by means of its contact with bifurcated upper ends 37 of the cutter 19, and the cutter 19 is restrained in its movement to the right as well by the 45 contact of its upper bifurcated portions 37 with the cutter 15 which upon compression of the spring 27 abuts against the lower end 38 of the housing 28, as by the stop 24.

In the operation of my invention it will 50 be apparent upon viewing the drawing that upon forcible depression of the head 13 the cutter 15 will remove only that part of the reproducer needle extending from the guide 23, between the bifurcated ends 37 of the cutter 19, against the stop 24 that on account 55 of the angularity of the disposition of the rest 21 relatively to the cutters 15 and 19, and the angularity of the guide 23 relatively to such rest, a very sharp point will be 60 given the reproducer needle; that by virtue of the coöperating action of the springs 27, 29 and 24 upon the cutters 15 and 19, such cutters will be forced into and held in the closest possible contact thus insuring a very 65 fine clean and sharp point; and that by

means of the action of the spring 32 the device will be automatically restored to operative position.

Having thus described my invention and illustrated its use what I claim as new, and desire to secure by Letters Patent is the following:

1. A cutter device comprising, in combination, pivotally movable base and head members, a cutter carried by said base, a second cutter carried by said head, a boss on said head adapted to be struck by the hand, said cutters being transverse to the pivotal plane of said parts, and outwardly pressing yieldingly resistant means for holding the cutters in contact before, while and after the edge of one of said cutters passes the edge of the other thereof, said yieldingly resistant means being disposed between said cutters and the pivotal mounting of said head and base. 75

2. A cutter device comprising, in combination, pivotally movable base and head members, a cutter pivotally carried by one of said members, the other thereof being provided with a cutting edge traversed by said cutter and with supporting means whereby material may be held in position to be acted upon by said cutter, and a yieldingly resistant device for restraining the 90 movement of the material and forcing the cutter into contact with said material. 95

3. A cutter device comprising, in combination, relatively movable base and head members, a cutter movably carried by one of said members and adapted to be moved in a plane at an angle to the path of movement of its support, the other of said members being provided with a cutting edge traversed by said cutter, a feed guide carried by said other member, and means in the line of movement of the cutter for first restraining the movement of material past the cutter and then forcing the cutter into operative position relatively to the said guide. 100

4. A cutter device comprising, in combination, relatively movable base and head members, a cutter movably carried by one of said members and adapted to be moved in a plane at an angle to the path of movement thereof, a feed guide carried by the other of said members on one side of the plane of movement of the cutter, and a spring stop on the opposite side of such plane for forcing the cutter in operative position relatively to the said guide. 110

5. A cutter device comprising, in combination, a base and a head mounted for movement relatively to each other, a cutter device mounted upon said base for movement relatively thereto, a cutter device mounted on said head for movement relatively thereto, the said cutter devices having traversing edges, means whereby material may be guided to the cutter, and yieldingly resistant 125

stop means adjacent said last mentioned means whereby the cutters are forced into contact during their traverse.

6. In a tool of the class described, a face 5 plate having an opening therein, a work holder adapted to guide the work to said opening, a knife and a member for advancing said knife and simultaneously pressing its cutting edge against said plate on the 10 side thereof opposite to the holder.

7. In a needle sharpener, the combination 15 of a pair of plier arms, a face plate rigidly secured to one of them, a fulcrum pin carried by the other of them, and a knife ful- crumed upon said pin, the pin being located 20 in the knife above and behind the cutting edge thereof.

8. In a needle sharpener, the combination 25 of two power elements traveling on the arc of a circle, a face plate mounted upon one of said power elements parallel to the axis thereof and approximately tangential to said arc and a knife pivoted to the other of said power elements upon an axis parallel 30 to the axis of said power elements.

9. In a needle sharpener, the combination 35 of two power elements, a face plate mounted on one of them, a knife pivot mounted upon the other of them, and a knife supported upon said pivot, the face plate and the cutting edge of the knife being parallel to the axis of the knife pivot, and said face plate extending substantially in the direction of 40 travel of said cutting edge.

10. In a needle sharpener, the combination 45 of a pair of plier arms, a face plate rigidly secured to one of them and arranged approximately tangential to the arc upon which the hereinafter mentioned knife edge

50 travels and a knife pivoted to the other of said arms upon an axis parallel to the axis of the plier arms, the cutting edge of the knife being also parallel to the axis of the plier arms.

11. In a needle sharpener, the combination 55 of a pair of plier arms, a face plate rigidly secured to one of said arms and having an opening therein, the portion of the plate adjacent to said opening being parallel to the axis of the plier arms, and a knife pivoted to the other of said arms upon an axis parallel to the axis of the plier arms, the cutting edge of the knife being also parallel to the axis of the plier

60 arms, and the point of pivoting of the knife to the arms being above and behind the cutting edge of the knife when the knife is moving forward, whereby the cutting edge is held in closed contact with the face plate when cutting.

12. In a needle sharpener, the combination 65 of a pair of plier arms, a face plate

secured to one of said arms and having an opening therein, a needle holder for guiding the needle to said opening, a knife, and 70 a knife-pivot carried by the other of said arms, and arranged parallel to the axis thereof, the location of the pivot in the knife being above and behind the cutting edge, thereby causing the edge of the knife to 75 adjust itself to the face plate during the act of cutting.

13. A cutter device comprising, in combination, a base, a stationary cutter comprising a plate having an edge adapted to support the material to be cut and a portion extending upwardly from said edge, an arm pivoted to the base, a cutter carried by said arm, a pivotal connection between said arm and said cutter, the axes of said pivots being parallel to said plate, and resilient means 80 for pressing the cutting edge of said movable cutter against said plate during the movement of said arm relatively thereto.

14. A cutter device comprising a base and head members, a stationary cutter attached to said base, a movable cutter mounted on said head, said stationary cutter having a portion extending above the cutting edge adapted to act as a guide for the edge of said movable cutter, a pivotal connection between said head and base members, the axis of which is arranged so that as the head member is depressed the latter approaches the plane of the stationary cutter, means for allowing the cutting edge of said movable cutter to move relatively to said head member, and means for resiliently holding said second cutter in contact with said stationary cutter.

15. A cutter device comprising, in combination, a pivotally movable base and head members, a stationary cutter carried by said base having a vertical face parallel to the pivot of said base and head members and having its cutting edge above the plane passing through said pivot perpendicular to the vertical face of the cutter, a guide portion extending above said cutting edge, a second cutter mounted on said head, means for allowing the cutting edge of said second cutter to move relatively to said head, and means for resiliently holding the cutting edge of said second cutter in contact with the said vertical face of said stationary cutter.

In testimony whereof I have hereunto signed my name in the presence of the two subscribed witnesses.

OSCAR L. SCALBOM.
